UNITED STATES PATENT OFFICE.

HENRY O. SCHMIDT, OF NEW YORK, N. Y., ASSIGNOR TO SIMONS, BROTHER & CO., PHILADELPHIA, PENNSYLVANIA.

DESIGN FOR A CANE OR UMBRELLA HANDLE.

SPECIFICATION forming part of Design No. 19,998, dated July 1, 1890.

Application filed April 15, 1890. Serial No. 348,123. Term of patent 3½ years.

To all whom it may concern:

- Be it known that I, HENRY O. SCHMIDT, a citizen of the United States, residing in New York, in the county and State of New York, 5 have invented and produced a new and original Design for Cane or Umbrella Handles, of which the following is a specification, reference being had to the accompanying drawing, forming part thereof.
- 10 In the drawing is shown a side elevation of a cane or umbrella handle illustrating my new design. A is the body part, and is of the shape shown, its central or middle portion swelling outward and being ornamented by spiral ribs 15 D. This body part is mounted on the top by a ball-shaped head B, separated from said body part by shaded work C and formed with annular depressed grooves E, arranged obliquely about it. The body part A is bounded 20 on the bottom by an annular band F, which is highly ornamented.
- The entire handle, outside of the parts F and C, may be plain or shaded, as desired.
- The handle is made of any suitable mate- 25 rial.
- Having now described my new design, what I claim as new, and desire to secure by Letters Patent, is—
- The design for cane or umbrella handles, 30 substantially as herein described and shown. In testimony of which invention I have hereunto set my hand.

HENRY O. SCHMIDT.
